ERASTUS D. WESTON, OF TAUNTON, MASSACHUSETTS.

Letters Patent No. 82,910, dated October 6, 1868.

IMPROVEMENT IN COOKING-STOVES.

The Schedule referred to in these Letters Patent and making part of the same

TO ALL PERSONS TO WHOM THESE PRESENTS MAY COME:

Be it known that I, ERASTUS D. WESTON, of Taunton, in the county of Bristol, and State of Massachusetts, have invented a new and useful Improvement in Cooking-Stoves; and do hereby declare the same to be fully described in the following specification, and represented in the accompanying drawings, of which—

Figure 1 is a longitudinal section of a stove provided with my invention.

Figure 2 is an under side view of its top plate and the bottom of the air-flue, the latter being shown as made in sections, having their joints provided with flanges, and arranged both in longitudinal and transverse directions relatively to the top plate.

Figure 3 is a transverse section of the top plate and air-flue, such section being taken between the boiler receiving-holes.

Figure 4 is another such transverse section, it being taken through the vertical end flanges of the air-flue plates.

Figure 5 is a vertical section taken through one side of the stove, or through one of its jambs.

The nature of my invention consists in the construction of the bottom of the air-flue in sections, with joints arranged transversely and longitudinally of the top plate, and provided with overlapping flanges, in order that the lateral and longitudinal expansion of the top plate of the stove may freely take place, without any danger of being so bound by the bottom plate or plates of the air-flue as to be cracked or warped. My improvement also avoids the danger of cracking the bottom plate of the air-flue.

The nature of my invention further consists in the combination of end flanges with the air-flue protection-plates, when they are extended partially across the space underneath the top plate, such end flanges being to extend up to the top plate, and, in connection therewith, extending the jambs of the stove up against the said end flanges, and to the top plate, as well as against the protection-plates, and projecting the bottom and the top plate beyond the jambs and end plates of the body of the stove; also, in constructing the said end flanges with notches or openings through them, to allow of the exit of air from the air-space into the flue, over the oven of the stove.

In the drawings, A denotes the body of the stove, and B the top plate, the latter being provided with boiler-openings, *a a*, and a circumscribing flange, *b*. The said flange is extended downward from the plate in manner as represented in the drawings, and is rebated, to receive the outer edges of a series of sectional plates, *c d e f g*. Each of the sectional plates, at one or each end of it, is furnished with a flange, *h*, to extend from it, and overlap the next adjacent sectional plate, so as to break the joint between the two, such joints and flanges being arranged in manner as represented.

The sectional plates are also provided with other flanges, *i*, to extend from them to the top plate, and against and inside of the flanges *b*, which circumscribe the boiler-openings, and project down from the top plate.

Furthermore, the two front sectional plates have air-holes, *l*, made through them, where they project beyond the front vertical end of the stove-body. The two lateral inner sectional plates have flanges, *m m*, extended from them up to the top plate, and against its circumscribing flange, such flanges *m m* being provided with notches or air-exit passages, as shown at *o o*.

Flanges *p p* extend from the lower surfaces of the top plate and the sectional plates, and against the jambs or body of the stove, such jambs or body being extended in its rear, as shown at *r s*, up to the top plate, and against the end flanges *m m*.

The above-described arrangement of the sectional plates, the end flanges *m m*, and the jambs, as set forth, saves the necessity and cost of extending the sectional plates back beyond the middle of the rear boiler-opening.

I am aware that it is not new to arrange an air-flue underneath and against the top plate of a stove, and directly over the main smoke-flue; leading from the fireplace over the top of the oven; consequently, I make no claim thereto.

What I claim is—

The bottom plate of the air-flue, as made of the five sections *c d e f g*, having their joints arranged transversely and longitudinally of the top plate, and provided with overlapping flanges, *h*, as described, in order that the lateral and longitudinal expansion of the top plate may freely take place.

I also claim, when the series of partition-plates of the air-flue is extended partially across the space underneath the top plate, the combination of the end flanges *m m* with such plates, and the extension of the jambs and end plates of the stove-body up against the said flanges, the partition and top plates, and these latter (with the partition and top plates) beyond the jambs and end plates or body of the stove, in manner as represented.

I also claim the said end flanges *m m*, as constructed with notches or openings *o o*, for the exit of air from the air-flue into the smoke-flue over the oven.

ERASTUS D. WESTON.
